UNITED STATES PATENT OFFICE.

FRANK M. GARLAND, OF NEW HAVEN, CONNECTICUT.

AUTOMATIC MACHINE-GUN MECHANISM.

SPECIFICATION forming part of Letters Patent No. 643,119, dated February 13, 1900.

Application filed May 1, 1899. Serial No. 715,122. (No model.)

To all whom it may concern:

Be it known that I, FRANK M. GARLAND, a citizen of the United States, residing at New Haven, in the county of New Haven and State 5 of Connecticut, have invented certain new and useful Improvements in Automatic Machine-Gun Mechanisms, of which the following is a specification.

This invention relates to the loading mechanisms of an automatic machine-gun in which the breech-block and barrel first move backwardly together under the recoil incident to the firing of a cartridge, and then as the barrel is drawn forward by the operating-spring the 10 breech-block is drawn still farther backward and held until the next cartridge is moved into its path, and the breech-block is thereby released, so as to thrust that cartridge into the breech of the barrel.

20 The present invention relates to and is an improvement on the mechanisms shown and described in the application for United States Letters Patent for an automatic machine-gun, filed January 27, 1899, and serially numbered 25 703,610; and the object is to simplify and make more perfect in action that mechanism of the gun set forth in that prior application which holds the parts, so as to accomplish the backward movement of the breech-block 30 while the barrel is drawn forward.

This invention resides in the arrangement, location, and action of the catches that engage and hold the pivot-block of the breech-block levers as it moves backwardly with the breech-block and barrel, so that the levers are required to oscillate and draw back the breech-block as the barrel moves forward, as more particularly hereinafter described, and pointed out in the claims.

40 Figure 1 of the accompanying drawings shows a side elevation of the feeding, loading, and firing mechanisms of a machine-gun that embodies the invention, the casing being cut in vertical central section to expose the interior. Fig. 2 is a plan of the pertinent portions of these same mechanisms, the casing being cut in horizontal central section. Fig. 3 is a transverse section on the plane indicated by the broken line A A of Fig. 2. Fig. 4 is a transverse section on the plane indicated by the broken line B B of Fig. 2. Fig. 5 is a detail view of the cartridge-lifter and catch-trip of the gun. Fig. 6 is an enlarged plan showing the catches and the trip. Fig. 7 is a side eleva-

tion showing the catches and connected parts. 55 Fig. 8 is plan of a modified form of the catches, and Fig. 9 is a transverse section looking at the end of the catches that are represented in Fig. 8.

As specified in the application referred to, 60 the barrel of the gun recoils when a cartridge is fired. With the barrel moves a frame 2, that is fastened to the breech end of the barrel and that is extended into the cylinder 3 at the rear end of the casing, Figs. 1 and 2. 65 On the extension 4 of this frame is fitted a block 5, and this block is thrust forwardly by a spring 6. Projecting from the sides of this block are arbors 7, and mounted upon these are the breech-block levers 8. The upper 70 ends of these levers are by a rod 9 connected with an arm 10, that extends upwardly from the breech-block 11, while the lower ends of these levers are by a rod 12 connected with the frame 2, Figs. 6 and 7. When the barrel and 75 breech-block recoil and move backwardly together, the block and the levers and connected rods move back with them as one part in the relative positions illustrated in 80 full lines in Fig. 7.

Supported by a pin 13, extending between lugs 14, formed on the interior of the casing, are the catch-levers 15. These catch-levers extend rearwardly from their supporting-pin, and their free ends are notched, so as to provide catch-shoulders 16. A spring 17, wound upon the pin 13, thrusts down the free ends of these levers, which are connected by a bar 18, so that they will operate together, Figs. 1 and 2. The outer ends of the breech-block-lever arbors extend beyond those levers and are provided with square shoulders 19. These shoulders are in the plane of the free ends of the catch-levers, and when the pivot-block and levers are moved back the catch-shoulders 16, when the catch-levers snap down, engage the shoulders 19 of the pivot-arbors and hold them temporarily against forward movement, as illustrated by the dotted lines in Fig. 7. When the breech-block levers 8 are 100 held in this manner by the retention of their pivot-block, the forward movement of the barrel and barrel-frame through the rod 12 causes the breech-block levers to oscillate from the position illustrated in full lines to 105 the position illustrated by dotted lines in Fig. 7, and this causes the breech-block to be drawn back along the frame from the breech

of the barrel. The parts remain in this position, with the pivot-block held back by the catch-levers 15, until the catch-levers are lifted from the shouldered ends of the breech-block-lever arbors, and then the spring 6 will thrust the pivot-block forward. The forward movement of the pivot-block will cause the breech-block levers to oscillate that the breech-block is slid along the frame and caused to close the breech of the barrel, as fully described in the prior application above referred to.

The cartridge-lifter 20, Figs. 1, 2, and 5, as specified in the prior application, is at the proper time thrown up by its spring 21 for lifting a cartridge into line with the breech-block. This lifter is secured to a shaft 22, that is supported by lugs 23, projecting from the interior of the casing, and the rear end of this is provided with a finger 24, that when the lifter is moved and the shaft rotated engages a lug 25, projecting from the side of one of the catch-levers. The engagement of this finger with the lug on the catch-levers lifts the catch-levers against the thrust of their spring, so as to release the catch-shoulders of the arbor and allow the block bearing the breech-block levers to be thrown forward, Figs. 1, 2, and 6.

30 The rearwardly-projecting catch-levers are very simple, and they do not occupy much space in the casing. These levers drop in front of the shoulders of the arbors and by positive engagement retain the breech-block levers until they are easily released vertically from the arbors at the proper time.

In the modified form illustrated in Figs. 8 and 9 the rearwardly-extending catch-levers 26, with their catch-shoulders 27, are pivoted 40 so as to move horizontally. These levers are provided with engaging arms 28, and a spring 29, pressing against the outer edge of one, causes both to be thrust into the plane of the end of the breech-block-lever arbors. In this 45 latter case the catch-shoulders engage with shoulders formed on the ends of the arbors instead of the top of the arbors. One of these levers is provided with a lug 30, and the shaft 31 of the cartridge-lifter has a finger 32, that 50 at the proper time engages the lug and causes the levers to move outwardly, so as to release the arbors and allow the pivot-block and breech-block levers to move forward. The catch-levers of both forms are so connected 55 that they operate together and both snap in front of the arbors for holding them and causing the breech-block to be moved backward. In the first form the catch-levers oscillate vertically and in the second form horizontally. Each is operated by a single spring 60 and each has a lug on one side adapted to be engaged by a finger projecting from the cartridge-lifter shaft.

I claim as my invention—

65 1. In an automatic machine-gun in combination with the movable barrel, the frame attached to the barrel, and the breech-block

movable along the frame, a pivot-block movable backwardly and forwardly along the barrel-frame, breech-block levers mounted upon the pivot-block and connected by links with the frame and also with the breech-block, rearwardly-extending catch-levers pivotally supported by the immovable casing, with catch-shoulders near their rear ends adapted to engage with and temporarily hold against movement the pivot-block with the breech-block levers, and mechanisms for releasing the catch-levers from the pivot-block, substantially as specified.

2. In an automatic machine-gun in combination with the movable barrel, the frame attached to the barrel, and the breech-block movable along the frame, a pivot-block movable backwardly and forwardly along the barrel-frame, levers mounted upon the pivot-block and connected by links with the frame and also with the breech-block, rearwardly-extending catch-levers pivotally supported by the immovable casing so as to move vertically, with catch-shoulders near their rear ends adapted to engage with and temporarily hold against movement the pivot-block levers, and mechanisms for releasing the catch-levers from the pivot-block, substantially as specified.

3. In an automatic machine-gun in combination with the movable barrel, the frame attached to the barrel, and the breech-block movable along the frame, a pivot-block movable backwardly and forwardly along the barrel-frame, levers connected by links with the frame and with the breech-block and supported by arbors projecting from the pivot-block, rearwardly-extending catch-levers pivotally supported by the immovable casing, with catch-shoulders near their rear ends adapted to engage with and temporarily hold against movement the arbors of the breech-block levers, and mechanisms for releasing the catch-levers from the arbors, substantially as specified.

4. In an automatic machine-gun in combination with the movable barrel, the frame attached to the barrel, and the breech-block movable along the frame, a pivot-block movable backwardly and forwardly along the frame that is attached to the barrel, levers connected with the breech-block and with the frame and supported by arbors projecting from the pivot-block, rearwardly-extending catch-levers pivotally supported by the casing, with catch-shoulders near their rear ends adapted to engage with and temporarily hold against movement the arbors, a cartridge-lifter, and a connection between the lifter and catch-levers whereby the upward movement of the lifter causes the catch-levers to release the breech-block-lever arbors, substantially as specified.

FRANK M. GARLAND.
